US00D594073S

(12) **United States Design Patent**
Kadoya

(10) **Patent No.:** **US D594,073 S**
(45) **Date of Patent:** **** Jun. 9, 2009**

(54) **HEAD FOR GOLF CLUB**

(75) Inventor: **Mamiko Kadoya, Kobe (JP)**

(73) Assignee: **SRI Sports Ltd., Kobe-shi, Hyogo (JP)**

(**) Term: **14 Years**

(21) Appl. No.: **29/300,615**

(22) Filed: **Apr. 18, 2008**

(30) **Foreign Application Priority Data**

Oct. 22, 2007 (JP) D2007-028944

(51) **LOC (9) Cl.** **21-02**

(52) **U.S. Cl.** **D21/744**

(58) **Field of Classification Search** D21/736-746;
473/324-331, 340-341, 251-256

See application file for complete search history.
